UNITED STATES PATENT OFFICE.

JESSE H. SANFORD, JR., OF PITTSBURGH, PENNSYLVANIA, ASSIGNOR TO GUARANTEED WATER ENGINEERING CORPORATION, OF PITTSBURGH, PENNSYLVANIA, A CORPORATION OF PENNSYLVANIA.

APPARATUS FOR CLEANING WELLS.

Application filed April 20, 1927. Serial No. 185,157.

My invention relates to apparatus for cleaning wells.

One object of my invention is to provide for cleaning wells by raising liquid from the well and discharging it into the walls of the well.

Another object of my invention is to provide apparatus for cleaning wells which raises the normal level of the liquid in the well by a pumping operation, discontinues the pumping operation and permits the currents incident to the lowering of the liquid level in the well to agitate the rock, sand and clay adjacent to the well.

Another object of my invention is to provide a plurality of jets externally of a well casing for breaking up zones of dense material that may accumulate around the casing.

Another object of the invention is to provide a pumping operation for raising liquid from a well and returning it to the well under pressure for flushing the liquid-bearing strata adjacent to the well.

A further object of my invention is to provide a system of apparatus for accomplishing the foregoing results.

In the operation of wells, the liquid-bearing strata is disturbed for a distance surrounding the well screen in order that liquid may collect more rapidly adjacent to the mouth of the well. In such areas there is a tendency for the formation of a dense deposit of fine particles of rocks and soil at a distance from the well casing, which deposit slowly reduces the flow of liquid to the well until, in some cases, the flow of liquid is substantially cut off. Since the velocity of the liquid adjacent to the well casing increases somewhat over its velocity at a distance, the dense wall of material builds outwardly from the casing to a distance of several inches.

In order to break down such an accumulation of material, I have provided a plurality of pipes that extend downwardly between the outer and inner casings into the liquid-bearing strata. By suitable pipe connections, I am able to pump water from the well to the ground surface and then discharge it back into the pipe under sufficient pressure to cause jets of water to play against and break down such deposits. During the operation of the jets, the level of the liquid in the well is raised considerably above its normal level by reason of the continued inflow of liquid from the

liquid-bearing strata and the return of the liquid from the pump. After the pumping operation has ceased, the water in the well recedes to its normal level and the current incident to its recession may be utilized for agitating and cleaning the particles of rock adjacent to the mouth of the well.

My invention is applicable to any type of well and may be used for pumping water, oil or any other fluid body.

In the accompanying drawings, which are a diagrammatic illustration of one form of apparatus by means of which the present invention may be carried out, the embodiment shown is for the purpose of illustration only, and not for the purpose of limiting the present invention, it being understood that changes in the operating conditions providing the results herein contemplated might be obtained in various ways.

In the accompanying drawings, Figure 1 is a view, partially in elevation and partially in section, of a well embodying my invention.

Figure 2 is a plan view of the well cap and pipe connections.

Figure 3 is a sectional view taken along the section line III—III of Fig. 2.

Figure 4 is a side view, partially in elevation and partially in section, of the pipe connections at the top of the well, and

Figure 5 is a view of a detail of the invention.

My invention may comprise in general, a well 1 having the usual outer casing 2, inner casing 3 and pump casing 4 driven by a suitable source of power 5 for discharging liquid through an outlet pipe 6. The well 1 extends downwardly through different layers of earth 7 and into a liquid bearing strata 8, such as a bed of gravel underlaid by a bed of rock 9. Suitable cleaning and flushing pipes 11 are disposed between the inner and outer casings 2 and 3, and are connected to the discharge pipe 6 in a manner hereinafter described.

In wells the fluid bearing strata 8 adjacent to the well casing is disturbed and broken up in an irregular zone indicated by the numeral 12. Such a zone acts as a reservoir for fluid preparatory to its entering the casing and is apt to become clogged by reason of the accumulation of a dense wall of particles at a distance from the well casing. Such a deposit grows outwardly from the well cas-

ing and may, in time, become sufficiently thick to materially retard or stop the flow of fluid therethrough. An important object of my invention is the agitation of the zone 12 by means of jets of liquid and by creating a current counter to the direction of the current of the fluid in the strata 8.

The outer casing 2 of the well extends downwardly through the different strata 7 until the top of the fluid bearing strata 8 is reached, where it terminates. The inner casing 3 extends downwardly into the disturbing zone 12 of the strata 8 and terminates in a filtering screen 13. A suitable base 14 may be adapted to the screen 13 or the screen 13 may close the casing, as desired. The pipes 11 extend downwardly between the inner and outer casings 2 and 3 to the strata 8 and thereafter the pipes 11 project downwardly into the zone 12 externally of the inner casing. The pipes 11 are provided with a plurality of openings 15 that open outwardly radially of the casing 3 and their lower ends provided with narrow orifices 16 through which particles of dirt are discharged from the pipes. The pipes 11 may be secured to a flared perforated base 14 by any suitable means.

The top of the well may be provided with a cement casing or cap 17 that also serves as a foundation for the source of power 5, which may be an electric motor or an engine. The motor 5 is connected to a shaft 18 that extends downwardly through the pump casing 4 for operating a pump 19, preferably of the turbine type.

The discharge pipe 6 is connected to the pump casing 4 by an elbow 21 provided with a packing gland 22 for the pump shaft 18. Referring particularly to Figures 2, 3 and 4, the discharge pipe 6 is provided with a main valve 23 and auxiliary valves 24 that are in turn connected to the several flushing pipes 11. The number of valves 24 and the flushing pipes 11 may be varied in accordance with the character of the well to which the invention is being applied. A waste pipe 25 is connected to the discharge pipe 6 between the elbow 21 and the valve 23 and is controlled by valve 26 for discharging the liquid into a waste pipe for reasons more fully hereinafter described.

Referring particularly to Figs. 3 and 4, each of the valves 24 is provided with a self-cleaning screen (not shown), and a mud cap 28.

Referring particularly to Fig. 5, I have shown a convenient method for inserting nozzles into the openings 15 in the pipes 11.

Assuming a dense deposit of earth to have been formed around the mouth of the well, the valve 23 is closed and the valves 24 opened, while the pump 17 continues to operate. This connection causes the fluid that is pumped upwardly through the casing 4 and

discharge pipe 6 to be returned through the screens 27 in the valves 24 to the several pipes 11. The fluid returning through the pipes 11 may be under an appreciable amount of pressure delivered by the pump 9 and is also at a considerable height above the normal fluid level in the well 1. Accordingly, the pressure at the openings 15 in the pipes is considerably in excess of the pressure in the strata 8. As a result, the fluid is discharged from the openings 15 in a plurality of jets that are directed radially outwardly from the casing 3. These jets attack and destroy the dense deposits by reversing the normal direction of movement of fluid therethrough. The openings 15 are self-cleaning by reason of the action of the fluid passing therethrough. In order to prevent the lower ends of the pipes 11 from becoming clogged with deposits of mud they are provided with orifices 16 through which downwardly directed streams of fluid escape adjacent to the screen 14.

This operation is continued for an appreciable length of time, dependent upon the extent of cleaning or flushing that must be given to the zone 12. After a predetermined time, the motor 5 is stopped, and the valves 24 closed. Thereafter, the head of fluid in the casing 3 tends to recede and as it does so, it moves outwardly through the openings in the screen 13 and agitates the rocks and gravel in the zone 12 with a lifting action, thereby further dissipating any collections of silt or mud.

Any accumulations of mud that may have accumulated in the valves 27 are removed from the mud caps 28 in order that only clean fluid shall be returned to the zone 8.

After a predetermined time, the valve 26 is opened and the pump started up, the fluid being discharged through the waste pipe 25 until it again runs clear, after which the valve 23 is opened, the valve 26 closed and the normal pumping operation continues indefinitely.

It will thus be seen that I have provided apparatus for flushing the zone of broken rock and gravel adjacent to a well screen, characterized by pumping the normal output of the well to the surface and then discharging it back into the well through a plurality of small pipes provided with openings such that the rocks and gravel surrounding the casing are subjected to a plurality of fluid jets tending to break down and wash away any deposits of dense material that might interfere with the normal flow of fluid to the casing. In order to practice such a method, I have devised a system of pipe connections by which the pump is able to discharge the fluid into the flushing pipes that are disposed between the inner and outer casings of the well.

While I have illustrated and described the present preferred embodiment of the inven-

tion, it is to be understood that it may be otherwise embodied without departing from the scope of the following claim.

I claim:

- 5 A well structure comprising a well pipe, pumping means disposed in the well pipe for drawing fluid from surrounding strata and discharging the fluid through the well pipe, a screen surrounding the well pipe, a flushing pipe outside the screen, the flushing pipe having a bottom terminal with a discharge orifice therein for restricting the end of the pipe and through which solid particles entering the pipe may be ejected, a plurality of 10 jets in the pipe at intervals therealong for directing streams of fluid into said strata in a direction counter to the movement of fluid toward said well pipe and a filter disposed in the flushing pipe between a source of flushing fluid and the jets, the combined areas of the openings in the jets and the bottom terminal having a relation to the cross-sectional area of the flushing pipe such that fluid ejected from the several openings is maintained under pressure by a fluid head in the flushing 15 pipe.
- 15

In testimony whereof I have hereunto set my hand.

JESSE H. SANFORD, JR.
